UNITED STATES PATENT OFFICE.

CHARLES H. LEHMAN, OF NEW YORK, N. Y., ASSIGNOR TO GENERAL ACOUSTIC COMPANY, A CORPORATION OF NEW YORK.

TELEPHONE SET.

1,281,593.

Specification of Letters Patent. Patented Oct. 15, 1918.

Application filed August 21, 1917. Serial No. 187,370.

To all whom it may concern:

Be it known that I, CHARLES H. LEHMAN, a citizen of the United States, residing at the city of New York, in the borough of 5 Manhattan and State of New York, have invented certain new and useful Improvements in Telephone Sets, of which the following is a full, clear, and exact description.

This invention relates to telephone sets 10 and more particularly to sets which are housed in a box or casing when not in use.

One of the objects of the invention is to provide an instrument of this character in which the transmitter and receiver are not 15 only protected by the casing, but also coöperate to effectually form a seal for each other when the box or casing is closed, thereby adapting the instrument for use upon ship-board, in mines, or in other localities where 20 there is excessive moisture present.

Other objects of the invention are to provide an instrument of the character referred to in which the transmitter and receiver are constructed and arranged so that they are 25 ready for use when the cover of the box is open without requiring the transmitter or receiver to be removed from the box or to be held in the hand while talking.

Other objects of the invention will be apparent from the detailed description herein-after to follow and the novel features of the invention will be set forth in the claims appended hereto.

In the drawings:

35 Figure 1 shown in perspective a telephone set with the casing open, the parts being constructed in accordance with the principles of the invention; and

Fig. 2 is a vertical section through the casing showing the position of the receiver and transmitter when in this position.

The telephone set comprises a transmitter 1 and a receiver 2 to which is connected a horn 3. The transmitter 1 is preferably 45 of the sensitive type which does not require the person talking to place his mouth close to the transmitter. Such transmitters are in common use at the present time and form a part of the well known "dictograph" system which are used as intercommunicating 50 systems in offices and in other places. As will be clear from Fig. 1, the transmitter comprises a cylindrical casing which incloses the diaphragm and has a series of holes or 55 openings 10 therein which are arranged in

annular form, through which the sound waves pass, which actuate the diaphragm of the transmitter. These openings are placed some distance from the edge of the transmitter to provide an annular surface 60 11. The receiver 2 is also of the well known type and is commonly known as a loud-speaking receiver which also does not require the ear to be placed close to the mouth of the horn 3 in order to have the transmitted sound waves clearly understood. The electrical parts of the receiver are inclosed within a casing 2' which is shown in Fig. 2 and which is moisture-tight except for the opening into which the small end of the horn 3 fits. The transmitter and receiver are mounted within a box which comprises a body portion 4 and a cover 5 which are hinged together as at 6. The cover 5 of the box is preferably provided with a flange so 75 that when the box is closed, it is substantially water-tight and moisture proof.

In the preferred form of the invention, the transmitter 1 is fastened to the cover 5 by a bracket 7 or in any suitable manner. 80 The receiver is fastened to the wall of the body portion 4 by brackets 8 and 9 so that it is rigidly mounted within the body portion of the box. The mouth of the horn 3 is provided with a rubber gasket 12 and the 85 transmitter and receiver are so mounted on the respective parts of the box that when the cover 5 of the box is closed, the rubber gasket 12 will bear against the annular surface 11 to form an effectual seal for both the 90 transmitter and receiver, which will prevent any moisture from entering the transmitter through the holes 10 and will also prevent any moisture from reaching the electrical parts of the receiver through the mouth of 95 the horn 3. Since the casings of both the transmitter and the receiver are moisture-proof at all other points, these parts when in closed position are, therefore, protected against moisture by their coöperation with 100 each other, as well as by the moisture-proof box in which they are inclosed.

The wires leading to the transmitter are indicated at 13 and 14 and the wires to the receiver at 15 and 16. These wires lead to a 105 small junction board 17 from which the wires, which connect the telephone set to another instrument, are connected by wires forming a cable 18. The cable 18 leads into the box or housing through an opening 19 110

which is surrounded by a rubber gasket 20 which serves to render the housing or box moisture-proof at this point, it being understood that the wires forming the cable are 5 properly covered with some form of water-proof coating.

The telephone set including its housing is shown in closed position in Fig. 2. When it is desired to use the telephone set, the cover 10 of the box or housing is opened until it is substantially at right angles to the body portion as is shown in Fig. 1. The instrument is then ready for use, since the person using the telephone set may stand with his 15 mouth directed toward the transmitter which will cause his ear to be adjacent the loud-speaking receiver. Both hands are therefore free during conversation over the set and since a sensitive transmitter and a 20 loud-speaking receiver are utilized, the operator may hear without difficulty even though his mouth and ear are at some distance from the transmitter and receiver permitting the instrument to be used with the least possible 25 inconvenience.

I claim:

1. A weather-proof box comprising two sections, one of which is movable with respect to the other, one section carrying a telephone 30 receiver and the other a telephone transmitter, both of which are wholly inclosed when the box is closed, the two instruments having

cooperating abutting surfaces which, when the box is closed, form a moisture-proof joint which excludes moisture from the interior of both instruments. 35

2. A weather-proof box comprising two sections, one of which is movable with respect to the other, and one having walls which overlap those of the other, a telephone 40 receiver fixed in one section, and a telephone transmitter fixed in the other section, said instruments having cooperating abutting surfaces which seal the interior of said instruments when the box sections are brought 45 into overlapping closed relation.

3. In a telephone set, a box comprising two hinged sections, a telephone transmitter mounted in one of said sections comprising a cylindrical casing having sound-wave 50 openings in its front section, a telephone receiver mounted in the other of said box sections having a horn through which the sound waves emanate, said transmitter being arranged to close the mouth of said horn when 55 the box is in closed position, and a rubber gasket carried by one of said parts for providing a moisture-proof closure between said transmitter and receiver when the box is in closed position. 60

In witness whereof, I subscribe my signature.

CHARLES H. LEHMAN.
